UNITED STATES PATENT OFFICE.

JOSEPH J. HERLBAUER. OF RICHMOND HILL, NEW YORK.

AUTOMOBILE-HORN.

1,229,453.

Specification of Letters Patent. Patented June 12, 1917.

Application filed April 5, 1916. Serial No. 88,997.

To all whom it may concern:

Be it known that I, JOSEPH J. HERLBAUER, a citizen of the United States, residing at Richmond Hill, county of Queens, 5 State of New York, have invented a certain new and useful Improvement in Automobile-Horns, of which the following is a full, clear, and exact description.

My invention relates to improvements in 10 automobile horns and has for its object to produce a horn which is durable, simple in construction and easy to manufacture. It further has for its object to produce a horn in which the disk-operating parts are all 15 mounted on and carried by the rear member of the horn. It further has for its object to provide a horn in which the casing, while it supports the diaphragm, does not have to be provided with a projecting flange for the 20 purpose of holding the diaphragm. It further has for its object to provide a horn with universal clamping means. It further has for its object to provide novel means for centering the diaphragm upon the casing. 25 It further has for its object to produce a horn in which the projections on the face of the agitating member are stamped out and formed upon a press, the projections having the general shape of exposed por- 30 tions of embedded balls. It further has for its object to provide a simple and efficient means whereby sections of pinion wires may be firmly secured to the parts driven by the pinions formed therefrom.

35 The following is a description of an embodiment of my invention, reference being had to the accompanying drawings, in which—

Figure 1 is a front elevation of a horn 40 embodying my invention with the front portion and diaphragm removed;

Fig. 2 is a side view of the horn complete;

Fig. 3 is a plan view of the same;

Fig. 4 is a section on the line 4—4, Fig. 1; 45 Fig. 4^a is a detail view of the diaphragm;

Fig. 5 is a side view showing a modification of the actuating means;

Fig. 6 is a rear view of the same;

50 Fig. 7 is a detail showing means for connecting the pinions to the parts operated thereby;

Fig. 8 is a front and a cross-sectional view 55 of the face portion of the agitating member; and

Fig. 9 is a side view of one of the pinion sections before assembling.

Referring more particularly to the drawings, in my horn there is a cup-shaped rear member 1, upon which is mounted a gear 60 wheel 2 whose revolving spindle or shaft 3 passes through the rear member 1. To this shaft is connected the actuating means 4. This actuating means can be moved in either direction to operate the horn. It is provided 65 with a spring 5 which normally tends to retract it to a normal intermediate position, from which it can be moved in either direction to actuate the horn. 4' is the handle of the actuating member, which in the form 70 shown in Fig. 1 is long enough to extend to the dash when the horn is located within the hood. It is connected to the actuating member by a universal joint 4^a so that it can be used when at an angle to the shaft. 75

Mounted upon the inside of the base is a spring 6 which bears upon the inner end of the spindle 3 which carries the first driving gear. This presses the driving gear toward the rear of the case so as to take up any lost 80 motion and prevent rattling. Mounted upon a fixed second spindle is a gear wheel 7 and a pinion 8 which meshes with the first gear 2; and mounted upon a third and fixed spindle 7' is the agitating device 9, which 85 is also provided with a pinion having teeth 10, said pinion meshing with the second gear wheel 7. The pinions of these two members are made from pinion wire, which is cut off in suitable lengths, the front portions being 90 slightly turned down so as to produce shoulders 10' thereon as shown in Fig. 9. The members 7, 14 and 10 are provided with holes 11 and internally projecting lugs 11', which enter one or more of the grooves between the ribs 10^a in the reduced portion of the cut off pinion wire section so as to prevent relative rotation of the pinion and its member. The forward portions of the projections upon the pinion member are swaged 95 down as at 12 so as to clamp the pinion securely to its member.

The spindle 7' is provided with a head and has its end screw-threaded. It is screwed into a threaded hole in the rear 105 member. To its projecting end a lock nut 7^a is applied. The spindle for the gear 7 is similar to the spindle 7' except that it is shorter.

The agitating member 9 is backed by one 110

or more metal sections 16 and is formed in a press so as to have ball-like projections 14 on its face and recesses 15 on its rear, which are formed in pressing out the ball-like projections. The rear members 16 are used so as to weight the agitating member so that it will have considerable momentum when actuated by the actuating means. In this device the pinion member 10 extends through both the portions 16 and 9 and its projections are swaged down to hold them together. These parts, after this swaging, are then case-hardened so as to produce hard agitating surfaces as well as a durable pinion. The agitating surfaces 14, as the agitator is revolved, pass a point which is concentric with the casing. Upon the forward edge of the rear member is mounted a diaphragm 17 having at its center a boss 18 through which passes a screw 18' held by a lock nut and provided with a hardened point which is engaged by the several agitating surfaces 14 as they pass beneath it. The diaphragm 17 is provided with projections 19, 19' which engage the face member 20 and the rear member 1 and act to center it within the casing. In front of the diaphragm is located the front portion of the casing 20, to which the horn 21 is connected. The front and rear sections of the casing are provided with holes 22, which register with holes 23 in the diaphragm and through these holes are passed screws or bolts 24 which hold the front and rear members together, clamping the diaphragm between them so that the diaphragm is securely held in position without the use of any protecting flanges upon the casing members. The holes 23 in the diaphragm are larger than the securing screws 24 so that the securing screws do not interfere with the vibration of the disk.

25 is a supporting bracket, riveted to a peripheral portion of the case and is engaged by the lower end of the diaphragm 17, thus assisting in the centering of the diaphragm within the case. It is provided with securing bolts 26 which are located at the angles of a square. These securing means serve to hold clamps 27, which, on account of the location of the securing means 26, can be placed so as to have their axes in line with the axis of the horn or at right angles thereto without changing the bracket.

55. In order to prevent the actuating member 4 and the first gear wheel 2 from coming into close engagement with the sides of the back member, I provide a washer 28 which is of slightly greater thickness than the thickness 60 of the back of the casing. Through this washer 28, as well as through the actuating member 4 and the gear 2, the spindle, which

is a square rivet, passes. The upsetting of the ends of this rivet holds the parts all together, while the washer referred to prevents the actuating member and the gear from being drawn so closely together as to bind upon the base. The washer has a round hole. It is case-hardened so as to present a durable wearing surface.

In the modification shown in Figs. 5 and 6, the actuating member is provided with a handle 30 rigidly fixed thereto as is desirable when the horn is to be mounted near the driver's seat or upon a motor cycle.

As will be evident to those skilled in the art, my invention permits of various modifications without departing from the spirit thereof or the scope of the appended claims.

I claim:

1. In an automobile horn, the combination of a cup-shaped containing member composed of a bottom and a flangeless circular wall perpendicular thereto, agitating means contained therein and surrounded by said perpendicular wall, a cupped face member, securing devices passing through the bottoms of said containing member and of said face member, a diaphragm clamped between opposing surfaces on said members, the portions of the members presenting said opposing surfaces and the periphery of said diaphragm being in line with the body of said perpendicular wall of said cup-shaped containing member.

2. In an automobile horn, the combination of a cup-shaped member, a face member, a diaphragm lying between said two members, means contained in said cup-shaped member for agitating said diaphragm, and means for securing said cup-shaped member and said face member together, said securing means passing within the inner walls of said two members and engaging the face of one and the bottom of the other, said diaphragm having centering projections located within and engaging the walls of said cup-shaped member.

3. In an automobile horn, the combination of a cup-shaped member, a face member, a diaphragm lying between said two members, means contained in said cup-shaped member for agitating said diaphragm, and means for securing said cup-shaped member and said face member together, said securing means passing within the inner walls of said two members, said diaphragm having centering projections located within and engaging the walls of the casing formed by said members and said securing means passing through openings in said diaphragm within said casing.

JOSEPH J. HERLBAUER.
